SCISSORS SHARPENER

George H. Piermann, Bellport, N. Y.

Application May 10, 1933. Serial No. 670,221

7 Claims. (Cl. 76—82.2)

This invention relates to a device particularly adapted for sharpening scissors. It is the object of my invention to provide an improved form of scissors sharpener; one that is relatively simple and hence cheap to manufacture, but one that is highly efficient in operation.

My invention will be readily understood by reference to the annexed drawing, wherein:

Figure 1 is a substantially full-size view of a preferred form of my invention.

Figure 2 is a view similar to Figure 1, but with the device turned 180 degrees, and showing the ends of the scissors blades in position on the sharpener.

Figure 3 is a view on a reduced scale of the device shown in Figure 1 turned to the left at an angle of 90 degrees, and with a pair of scissors in position to start the sharpening operation.

In the drawing, the sharpening device includes a handle 1 of any suitable material, such as wood, having a central bore 2, in the upper end of which is positioned a metallic collar 3 having a tapped hole to receive a set screw 4. Fitting the upper end of the handle 1 is a ferrule 5 through which the set screw 4 passes. The end of the ferrule 5 is provided with oppositely disposed slots through which pass the arms 6 and 7 of a guide and support member 8. It is to be understood that the material of the handle under the ferrule, where the arms 6 and 7 pass through is cut away or recessed to provide space for the arms 6 and 7, and they may be fastened to the ferrule in any satisfactory manner as by staking or indenting the edge of the ferrule at 9 into the arms 6 and 7.

The guide and support member 8 has a centrally located hole 10 through which passes a sharpening member 11 preferably made of hardened steel and the outer surface provided with a large number of flutes as in many forms of "steels" used in table carving sets. The sharpening member or steel 11 is adapted to fit into the collar 3 and into the counterbore 2 and can be adjusted longitudinally of the handle and fastened in position by the set screw 4. The guide and support

member 8 has two specially formed surfaces 12 and 13 which are arranged in offset relationship, one to the other, as shown in the various views. However, it is to be noted that the offset 14, on one edge, is preferably somewhat greater than the offset 15 on the opposite edge, so that the two surfaces 12 and 13 are not in the same parallel planes, but the lines of the offsets 14 and 15 are substantially on the axial center of the sharpening member or steel 11.

This arrangement is so that when the blades 16

and 17 of the shears are placed against their respective surfaces 12 and 13, and straddling the sharpening member 11 about as indicated in Figure 3, the cutting edges 18 and 19 of the blades, which are at a sharp angle with respect to the blades, will be brought into proper engagement with the sharpening member 11 as is clearly indicated in Figure 2.

In sharpening the scissors, the device is held by the handle, for example in the left hand, with the device preferably turned 90 degrees to the right from the position shown in Figure 1, and then the scissors are placed on the guide and support member 8 about as shown in Figure 3. The scissors are then operated just as though a cutting operation were to be performed with a slight drawback on the hand. This causes the cutting edges 18 and 19 of the blades to pass lengthwise across the serrations or flutes on the sharpener 11, thereby sharpening the cutting edges 18 and 19.

It has already been pointed out that the steel 11 may be adjusted longitudinally or rotated in the handle so that new surfaces may be readily brought into position, to be engaged by the scissors blades, and from the construction of the guide and support member 8, as has been described, the cutting edges 18 and 19 of the scissors blades will be brought, at the correct angle, against the steel 11, without the exercise of any great amount of attention on the part of the operator who has only to see that the blades 16 and 17 are placed against the surfaces 12 and 13 in the manner set forth.

Certain changes in details may also be made without departing from the spirit of the invention. For example, the fine serrations or flutes on the sharpener 11 may be arranged in a spiral manner, and the ferrule 5 may be thick enough or so constructed as to be directly tapped for the set screw 4, thereby entirely doing away with the collar 3.

Having thus described my invention, what I claim is:

1. A scissors sharpener including a handle, a guide and support member carried by the handle, said member having two laterally offset surfaces with a hole passing through parts of both surfaces at the offset, and a sharpening member extending from the handle through said hole.

2. A scissors sharpener including a handle, a guide and support member carried by the handle, said member having two laterally offset surfaces positioned in different planes lying at an angle to the axis of the handle, said guide and support

member having a hole therethrough where the offset joins said two surfaces, and a sharpening member adjustably carried by the handle and extending through said hole.

5 3. A scissors sharpener as set forth in claim 2, further characterized in that the said different planes are not parallel.

10 4. A scissors sharpener including a handle, a guide and support member having arms extending into and fastened to one end of the handle, said guide and support member having surfaces disposed at an angle to the axis of the handle and located in different planes at a slight angle to each other, and a sharpening member adjustably 15 carried by the handle and extending through said guide and support member at the junction of said surfaces and in operative relation to said surfaces, whereby when the scissors blades are placed on said surfaces on opposite sides of said sharpening member, the cutting surfaces of the blades 20 will make the proper angular contact with said sharpening member.

25 5. A scissors sharpener including a handle, a guide and support member carried by the handle, said member having two laterally offset surfaces lying in planes making an angle other than a right angle with the axis of the handle, and a sharpening member passing through said guide

and support member at the junction of said surfaces and carried in adjustable relation with said surfaces, whereby when the scissors blades are placed on said surfaces on opposite sides of said sharpening member, the cutting surfaces of the blades will make the proper angular contact with said sharpening member.

80

6. A scissors sharpener including a handle, a guide and support member carried by the handle, said member having two laterally offset surfaces, and a sharpening device passing through said guide and support member at the junction of said surfaces and positioned so the plane of the offset substantially includes the axis of the sharpening device which extends through and beyond said surfaces at the offset.

85

7. In a device of the class described, a handle, a circular sharpening member adjustably and removably carried by the handle, a guide and support member bridging said sharpening member, said guide and support member having unequal offsets on opposite sides of said sharpening member, thereby forming two surfaces disposed in different planes at an angle to the axis of the sharpening member to receive the blades of the scissors substantially as and for the purposes described.
